UNITED STATES PATENT OFFICE

LELAND S. HAMER, OF LONG BEACH, CALIFORNIA, ASSIGNOR TO HAMER OIL TOOL COMPANY, LIMITED, OF LONG BEACH, CALIFORNIA, A CORPORATION OF DELAWARE

PACKER FOR PUMP LINERS

Application filed July 25, 1928. Serial No. 295,244.

This invention has to do with a packer for a pump liner or the like, and it is a general object of the invention to provide a simple, inexpensive, effective, and easily handled 5 packer for sealing one member within another, for instance a liner in a cylinder. Liners are often mounted in cylinders, particularly in pump cylinders, it being common practice to provide a packing gland between 10 the liner and cylinder to carry rubber packing, or the like. In practice the rubber packing ordinarily used in this class of work is compressed tightly in the gland between the liner and cylinder so that it is difficult, in fact 15 in some cases almost impossible, to remove the liner for purpose of repair or replacement.

An object of this invention is to provide a packing or packer for use in packing two members such as a liner in a cylinder and 20 which readily releases or frees the liner when it is desired to remove the liner from the cylinder.

Another object of the invention is to provide a packer of the character mentioned 25 which is effective and dependable in making a fluid-tight joint between the members to be packed.

It is a further object of this invention to provide a packer of the character mentioned 30 which is simple and inexpensive of manufacture and also simple and convenient to handle.

The various objects and features of my invention will be best and more fully understood 35 from the following detailed description of a typical form and application of the invention, throughout which description I refer to the accompanying drawings, in which:

Fig. 1 is a longitudinal detailed sectional view taken through a typical pump cylinder showing a liner in the cylinder and packing embodying the present invention in operating position in the gland provided between the liner and the cylinder. Fig. 2 is an enlarged detailed transverse sectional view taken as indicated by line 2—2 on Fig. 1. Fig. 3 is a sectional view taken as indicated by line 3—3 on Fig. 2, and Fig. 4 is an enlarged detailed sectional view of the packer provided 50 by this invention.

The packer provided by my present invention is applicable, generally, to packing glands, or for packing between two members arranged one within the other, it being particularly useful as applied to packing glands 55 between cylinders and liners. For purpose of example I will refer to the invention as applied to a pump construction wherein it will be described as arranged between a pump cylinder and a liner for the cylinder. In the drawings I have illustrated a typical pump construction embodying a cylinder 10 closed at its ends by suitable heads 11, a liner 12 mounted in the cylinder, a clamp 13 engaging the liner to hold it in the cylinder, a clamp screw 14 carried by one of the heads 11 to actuate the clamp 13, a piston 15 slidably fitting the liner, a piston rod 16 connected to the piston and extending through one of the heads 11, and various other parts common to 60 apparatus of this general character.

In the drawings I have shown a typical or simple form of liner mounting. In the case illustrated, the opening of the cylinder has an enlargement 17 extending inwardly from one end and terminating in a shoulder 18. The liner 12 has an outwardly extending enlargement or flange 19 on one end fitting the enlargement 17 of the cylinder. The flange 19 on the liner has a shoulder 20 facing the shoulder 18 in the cylinder, and the parts are arranged and proportioned so that there is a chamber or space between the shoulders 18 and 20 forming a gland to carry packing. 75

The packer or packing provided by the present invention is intended to be used in a gland such as I have above described. The packer comprises, generally, two sections, namely, an inner or liner section A and an outer or cylinder section B. The liner section 80 A is adapted to more or less closely fit or engage the exterior of the liner 12 and freely fit the opening or enlargement 17 in the cylinder while the cylinder section B is adapted to more or less closely fit the opening or enlargement 17 in the cylinder and freely fit the liner. 95

The liner section A comprises a body 25 in the form of a ring adapted to fit between the liner and the wall of the opening 17 of the 100 cylinder.

cylinder and to engage or seat against one of the shoulders, for instance the shoulder 18. The body 25 of the liner section A preferably fits more or less closely around the liner 12 and fits the opening 17 with passing or sliding clearance. Both sections of the device are formed mainly of rubber, or the like, it being preferred, however, to provide a reinforcing ring 26 of metal in the body 25, as illustrated in the drawings. The ring may be a flat washer-like member. It is preferably provided with a plurality of openings 27 into and through which the rubber extends causing the ring to be securely and permanently embedded in the body of rubber. In practice the metal ring may be completely sealed or covered in the rubber.

In accordance with my invention, the liner section A has a sleeve-like extension 30 projecting from the body 25 to fit or seat on the liner 12 and to cooperate with the cylinder section B. The sleeve extension 30 preferably has a uniform inside diameter fitting more or less closely over or around the liner 12. The exterior or face 31 of the sleeve extension is tapered or made outwardly convergent, that is so that it converges from its inner end where it joins the body 25 to its outer or projecting end.

The cylinder section B of the packer is made to fit the opening 17 in the cylinder and is made complementary to the section A, that is it is made to fit or cooperate with the section A to fill the gland or packing chamber, as clearly illustrated throughout the drawings. The section B may include a body part 35 in the form of a ring corresponding generally to the body part 25 of the section A. A metal reinforcing ring 36, similar to the ring 26, may be provided in the body 35 of the section B. A sleeve extension 37 is provided on the body 35 to fit or seat in the opening 17 of the cylinder and to have a tapered inner face 38 to fit or seat against the exterior 31 of the sleeve extension 30 of section A. The inner face or interior 38 of the sleeve extension 37 is tapered to correspond to the exterior 31 of the extension 30, and the sleeve extensions 30 and 37 are of the same length. It will be noted from inspection of the drawings that the two sections fit together so that the outer ends of the sleeve extensions engage the bodies of the sections when the sections are in operating position.

In using the packer the two sections are assembled or arranged together in the gland or packing chamber as shown throughout the drawings, the liner section A having a natural tight fit or seat on the exterior of the liner and the cylinder section B having a natural tight fit or seat in the opening 16 in the cylinder. The bodies 25 and 35 of the sections engage the shoulders 18 and 20 at the ends of the gland so that the sleeve extensions 30 and 37 of the sections wedge together

gather and expand each other as the screw 14 is operated to tighten the clamp 13 against the liner.

In practice it is preferred to apply grease, or the like, between the faces 31 and 38 of the packer sections, it having been found that this facilitates freeing of the sections when the liner is removed. It will be obvious from the drawings that the formation and fitting together of the sections as above described causes the packer to make a tight, dependable seal between the liner and cylinder. The most important feature of the invention, however, is the fact that the sections readily separate when the clamp is released allowing the liner to be freely removed from the cylinder. It has been found that under actual operating conditions the sections of the packer part freely, making it unnecessary to use complicated and expensive liner pullers such as have to be employed when removing a liner packed in a cylinder by means of the ordinary packing.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. A packer of the character described including, two separable sections each including a cylindrical part and a tapered extension on the cylindrical part, the extensions being shaped to fit one into the other, the engaging faces of the extensions being tapered, the end of the extension of one section engaging the shoulder beyond the cylindrical part of the other section.

2. A packer of the character described, including two separable complementary annular sections, each including a cylindrical part and a tapered extension on the cylindrical part, the extensions being shaped to fit one into the other, the engaging faces of the extensions being tapered, the end of the extension of one section being in engagement with a radial side of the cylindrical part of the other section.

In witness that I claim the foregoing I have hereunto subscribed my name this 22nd day of June, 1928.

LELAND S. HAMER.
